COSTUMER

Luther G. Simjian, Stamford, Conn.

Application May 10, 1949, Serial No. 92,307

2 Claims. (Cl. 211—36)

1

This invention relates to a costumer of that type adapted to be folded for ready storage, and adapted when in unfolded position, to be stable and to support adequately a number of garments. It is the object of my invention to contribute a costumer of the particular class that will be economical to manufacture, use a minimum of parts, support the usual number of garments, and lend itself readily to folding for storage.

As one feature of my invention whereby the results thereof are obtained, I utilize a main frame member terminating in opposed legs relatively to which an additional supporting leg is rotatable into and out of supporting position. Further, when the supporting leg is moved into supporting position relatively to the costumer, it supports thereon a shoe shelf that is allowed to move into a folded position when the supporting leg itself is folded against the opposed legs of the main frame of the costumer.

As a further feature of my invention, the upper end of the main frame of the costumer supports a coat carrying member that in turn carries a trouser supporting bar arranged to move automatically for clamping trousers draped thereover, so that the trousers will be held securely in draped position.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of claims appended hereto. Those skilled in the art will appreciate that the conception on which my disclosure is based may readily be utilized as a basis for the designing of other structures for carrying out the several purposes of my invention.

Referring now to the drawings, Fig. 1 is a perspective view of the costumer of my invention. Fig. 2 is a view of part of Fig. 1 with certain elements broken away and thereby better illustrating the construction of my invention. Fig. 3 is a view of the parts of Fig. 2 with the said parts in a compact folded position.

Referring now more particularly to the drawings, the main frame of my invention comprises a vertical strut 10 to which is secured at its lower end a cross plate 11 terminating in opposed legs 12 and 13. If desired, cross plate 11 may be formed as an integral part of the vertical strut 10. At its upper end the vertical strut 10 has formed integrally therewith a coat hanger 14 over

2

which may be hung a coat as those skilled in the art will appreciate. The part 15 of the coat hanger may support a hat or some other garment such as a shirt, etc.

Pivoted to the opposed lower ends of the coat hanger 14 are levers 16 supporting therebetween a bar 17 over which may be draped trousers 18. A mere application of the weight of the trousers to the bar 17 will move the bar 17 firmly toward the strut 10 thereby clamping between the strut 10 and the bar 17 the trousers 18. Thus, the mere application of the weight of the trousers to the bar 17 is adequate to insure the gripping of the trousers and their maintenance in draped relation to the bar 17.

A metal plate 19 is applied to the lower end of the strut 10, the plate 19 supporting one end of a pivot shaft 20. The upper end of the pivot shaft 20, which may take the form of a long nail, is carried by a narrow downwardly inclined shelf portion 21 that is secured to the upper end of the cross plate 11 and the strut 10. Pivotally mounted about the pivot shaft 20 is a supporting leg 22 having opposed foot portions 23 and 24. When the costumer is folded, the leg member 22 is maintained in the position illustrated in Fig. 3 with its plane parallel to the plane of cross plate 11. When it is desired to utilize the costumer, the leg member 22 is merely rotated into the transverse position relatively to the cross plate 11 illustrated in Fig. 2. It is quite obvious that leg member 22 will then coast with the feet 12, 13 of the cross plate 11 to hold the costumer in a stable position.

A pair of hinges 25 pivotally support a shoe shelf 26 relatively to the shelf portion 21, the shoe shelf 26 moving on the hinges 25 from the position of Fig. 3 to the position of Figs. 1 and 2. Obviously, when it is desired to use the costumer, the shoe shelf 26 moves into the position of Figs. 1 and 2 from the position of Fig. 3 and is there supported by the leg member 22 with the upper surface 27 of the said leg member underlying the lower surface of the shoe shelf 26.

It seems rather obvious now that the costumer will adequately support the usual items of apparel, including a pair of shoes, and that the costumer may readily be folded into the position of Fig. 3 for storage within a closet or the like. It is further apparent that my costumer requires a minimum of parts and is extremely simple to manufacture and assemble. I believe that the considerable merit of my invention will now be apparent to those skilled in the art.

I now claim:

1. In a costumer of the class described, a narrow vertically extending post-like main frame member terminating at its lower end in a pair of spaced opposed legs the upper edges of which extend laterally from each side of said post-like main frame member, the upper end of said main frame member adapted to carry a coat supporting device, a supporting leg pivoted relatively to said post-like main frame member and said opposed legs for movement from a position parallel to the plane of said opposed legs to a plane at right angles to said opposed legs whereby with said opposed legs to support said post-like main frame member in a vertical position, and a shelf member extending from said upper edges of said spaced opposed legs and inclined downwardly therefrom to rest on said supporting leg member whereby to support shoes with their heels overlying said upper edges.

2. In a costumer of the class described, a narrow vertically extending post-like main frame, a wide plate-like cross member secured to the lower end of said post-like main frame and terminating in widely spaced opposed legs while presenting an upper thin edge extending laterally from said narrow post-like main frame at each side thereof, a supporting leg member, a narrow shelf coextensive with said plate-like cross member and secured to its upper edge and overlying part of said supporting leg member, a vertical pivot for said supporting leg member whereby said leg member pivots from a position parallel to the plane of said cross member and its opposed legs into a plane at right angles to the plane of said

opposed legs whereby with said opposed legs to support said post-like main frame member in a vertical position, a shoe shelf, means pivoting said shoe shelf to said narrow shelf so that it hangs substantially parallel to the plane of said opposed legs when the plane of said supporting leg member is also parallel to said opposed legs, and said shoe shelf moving on its pivot to allow swinging of said supporting leg into its plane at right angles to said opposed legs and said plate-like cross member, the upper edge of said supporting leg member then supporting thereon the shelf.

LUTHER G. SIMJIAN.
